UNITED STATES PATENT OFFICE

150,308

DESIGN FOR A FRUIT JUICE SQUEEZER

Frank N. Mariani, Washington Heights, N. Y.

Application August 14, 1946, Serial No. 132,524

Term of patent 14 years

(Cl. D89—1)

To all whom it may concern:

Be it known that I, Frank N. Mariani, a citizen of the United States and residing at New York city, in the county and State of New York, have invented a new, original, and ornamental Design for Fruit Juice Squeezers, of which the following is a specification, reference being had to the accompanying drawing, forming a part thereof wherein:

Fig. 1 is a perspective view of my fruit juice squeezer showing my new design illustrating the squeezer closed and the stabilizing means retracted.

Fig. 2 is a perspective view of the squeezer in fully opened relation with the stabilizing means withdrawn from the base and the telescopic handle extended.

Fig. 3 is a plan view of Fig. 1.

Fig. 4 is a front view of Fig. 1, and
Fig. 5 is a rear view of Fig. 1.

I claim:

The ornamental design for a fruit juice squeezer, substantially as shown.

FRANK N. MARIANI.
